US0D1054131S

(12) **United States Design Patent** (10) **Patent No.:** **US D1,054,131 S**
(45) **Date of Patent:** **** Dec. 10, 2024**

(54) **VACUUM CLEANER BODY**

(71) Applicant: **LG ELECTRONICS INC.**, Seoul (KR)

(72) Inventors: **Nerry Son**, Seoul (KR); **Hoil Jeon**, Seoul (KR); **Seongmin Kim**, Seoul (KR); **Donghwan Lee**, Seoul (KR); **Jaeyoung Kim**, Seoul (KR)

(73) Assignee: **LG ELECTRONICS INC.**, Seoul (KR)

(**) Term: **15 Years**

(21) Appl. No.: **29/861,754**

(22) Filed: **Dec. 2, 2022**

(30) **Foreign Application Priority Data**

Sep. 16, 2022 (KR) 30-2022-0037949

(51) **LOC (14) Cl.** **15-05**

(52) **U.S. Cl.**

USPC **D32/17**

(58) **Field of Classification Search**

USPC ..... D15/199; D21/526, 578; D32/15, 16, D32/17, 18, 21, 23, 25, 31, 32, 38, 39 CPC ... (57) **CLAIM**

The ornamental design for a vacuum cleaner body as shown and described.

DESCRIPTION

FIG. 1 is a top, front, left-side perspective view of a vacuum cleaner body showing our new design;

FIG. 2 is a bottom, rear, right-side perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

The broken lines depict portions of the vacuum cleaner body that form no part of the claimed design.

1 Claim, 8 Drawing Sheets
